UNITED STATES PATENT OFFICE.

BENJAMIN F. BLANCHARD, OF FULLERTON, CALIFORNIA.

HYDRAULIC UNDERREAMER.

Application filed January 28, 1926. Serial No. 84,342.

This invention relates to improvements in hydraulic rotary underreamers used in well drilling, and may be considered as an improvement over the underreamer disclosed 5 in my prior Patent, No. 1,548,578, issued August 4, 1925.

An object of this invention is to provide an improved hydraulically operated underreamer which is of improved construction 10 and which is so designed that it is very difficult for parts to get out of order.

Another object of this invention is to provide an improved cutter construction upon an underreamer.

15 A further object of this invention is to provide an improved mechanism for admitting fluid to the interior of the lower pipe or drill pipe above the tool, so that pressure will not build up within the tool during 20 lowering to cause the reamer to be expanded when it is not so intended.

With the foregoing and other objects in view which will be made manifest in the following detailed description and specifically 25 pointed out in the appended claims, reference is had to the accompanying drawings for an illustrative embodiment of the invention, wherein:

Figure 1 is a vertical section through the 30 improved underreamer shown in fully expanded position,

Fig. 2 is a view similar to Fig. 1, illustrating the reamer in fully contracted position.

Fig. 3 is a partial view in section illustrating the details of construction of the cutters and blocks on which the cutters are 35 mounted, the reamer in this view being shown in fully expanded position,

Fig. 4 is a partial view in side elevation 40 taken substantially in the direction of the arrow 4 upon Fig. 3,

Fig. 5 is a horizontal section taken substantially on the line 5—5 of Fig. 3,

Fig. 6 is a view similar to Fig. 5 illustrating the reamer in contracted position, 45 and may be considered as a horizontal section taken upon the line 6—6 of Fig. 2,

Fig. 7 is a vertical section illustrating the details of construction of the valve and 50 ports which admit fluid to the interior of the drill pipe above the reamer on lowering the reamer into a well, and

Fig. 8 is a horizontal section taken on the line 8—8 of Fig. 7.

55 Referring to the accompanying drawings wherein similar reference characters desig-

nate similar parts throughout, the details of construction of the reamer proper are as follows: The reamer consists of a cylindrical body 10 having an interior cylindrical surface. In this body there are formed two diametrical slots 11, and within it there is positioned a conical wedge or mandrel 12, in which is formed a longitudinal bore 13. This wedge is threadedly connected to the body 60 10, as indicated at 14, and constitutes a wash pipe terminating in a cylindrical section 15. Blocks 16 are vertically slidable in the two slots 11. These blocks have their inner faces engageable upon the conical wedge or mandrel 12 so that when they are lifted, they will be expanded or forced radially outwardly 65 through the slots 11. Each of the blocks has its inner face presenting a conical surface which is complementary to the conical 70 surface on the wedge 12 when the blocks are in their uppermost position. They are also provided with lateral wings 17 which extend laterally beyond the sides of the slots 11, and these lateral wings have their forward surfaces cylindrical in shape so that they will 75 fit against the interior cylindrical surface of the body 10 when the blocks are in their uppermost position. In each of the blocks there is positioned a vertical pin 18 which 80 is locked in place as by a pin 19, and a cutter or reamer 20 is rotatably mounted upon each pin 18. A bore 21 is formed in each block 16 so that a spike or punch can be inserted 85 therein to knock loose the vertical pin 18 whenever it is desired to replace the cutters 20 or to replace the pins 18.

Adjacent the lower end of each of the blocks 16 there is formed a downwardly and inwardly inclined pin 22 which is threaded. A bushing 23 is threaded onto this pin and a cutter 24 is rotatably mounted on this bushing between washers 25. Each of the cutters 24, because of the above described construction, is rotatable about axes which are upwardly and outwardly inclined. They are so formed as to provide a surface 26 which on the lower portion of the cutter is approximately vertical, and also a surface 27 which on the lower portion of the cutter is approximately horizontal. It will be understood that these cutters do the major portion of the cutting, the cutters 20 being used mainly for merely smoothing up the hole thus reamed.

Supplemental blocks 28 are secured to the pins 22 as by cap screws 29, and these blocks

are similar in cross section to the blocks 16 in that they have the lateral wings 17. The length of the slots 11 is approximately twice the overall dimension of the blocks 16 together with the supplemental blocks 28.

As a means for raising the blocks 16 together with the supplemental blocks 28 within the slots 11, a cylindrical piston 30 is slidable within the body below the blocks 10 and arranged about the conical wedge or mandrel 12. This piston is illustrated as being provided with a cup or packing leather 31 held in place by a ring 32 which is fastened by screws 33. On the interior of the 15 body there is positioned a brass or bronze liner 34 against which the packing leather 31 bears. The interior of the piston 30 has a conical surface which is complementary to the conical surface of the mandrel or conical 20 wedge 12, when the piston 30 is in its uppermost position, that is, when it has lifted the blocks 16 to that position in which they encounter the upper ends of the slots 11. In 25 the lower end of the body 10 there is screwed a sub 35 having a division web or a blanked off portion 36. In this blanked off portion there are formed bores or passages 37, permitting circulation fluid which is forced 30 downwardly within the bore 13 to pass there-through, but at the same time causing a pressure to build up within the body 10 about the cylindrical portion 15 of the mandrel or conical wedge 12, so that when pressure is applied to the fluid flowing down- 35 wardly through the bore 13, the pressure developed within the body 10 will cause the piston 30 to rise and thus lift the blocks 16. It will be noted that when the blocks are 40 completely lifted their upper ends engage the tops of the slots 11, the forward surfaces of the wings 17 engage the interior surface of the body while the inner surfaces of the blocks 16 engage and fit the conical wedge 12 and also the piston 30 fits the conical wedge 45 12, thus forming a tight, rigid construction during the reaming so that there will be no wobbling or loosening of the parts.

On lowering the underreamer into the hole by the drill pipe D, it will be understood that 50 the well hole is full of liquid and it will flow upwardly through the bores 37 in the blanked off portion 36 of the sub 35. Because of the fact that a quick lowering of the reamer into the hole might cause this fluid 55 to build up a pressure on the under side of the piston 30, causing the reamer to be expanded during the lowering, there is provided a particular valve construction at the upper end of the reamer which will admit 60 fluid from the hole into the drill pipe D to eliminate this.

In the body of the conical wedge or mandrel 12, which extends above the cylindrical body 10, there are formed a plurality of radial ports 38, and on its interior there is

formed an annular recess 39 with which the ports communicate. On the interior of the upper end of the conical wedge or mandrel 12 there is screwed a valve seat 40 having a vertical bore 41 therethrough and providing a seat for the ball check valve 42. The ball check valve 42 is maintained adjacent its seat by a cage 43. The lower end of the bore 41 is closed by a plug 44, and in the body of the valve seat 40 there are formed 70 radial ports 45 which communicate with the recess 39. As clearly indicated in Fig. 8, vertical passages 46 are formed in the body of the valve seat 40 between the radial ports 45, so that they will have no communication 75 with the radial ports.

The operation of this construction is as follows: When fluid is being forced downwardly within the drill pipe D, the ball 42 remains upon its seat and all of the fluid is caused to flow downwardly through the passages 46, passing downwardly within the conical wedge 12 in the previously described manner. However, on lowering the reamer into the well, fluid may flow upwardly within the passages 37, but the larger portion of the fluid will be caused to fill the drill pipe D by flowing through the ports 38 into the annular recess 39 and through the ports 45, flowing upwardly through the bore 41 beneath the check valve 42. After the device has been lowered into the well, fluid is forced downwardly within the drill pipe, the check valve 42 again seats and the fluid is all caused to flow through the vertical passages 46. In this manner it will be noted that fluid can enter the drill pipe D above the tool so that no pressure will be developed on the under side of the piston 30, causing it to be lifted during the lowering into the 105 well hole.

From the above described construction it will be appreciated that an improved hydraulically operated underreamer is provided which is simple in construction and very rugged in design. Furthermore, when the reamer is in expanded position, all parts will be snugly fitting or resting against each other, forming a solid structure during the 110 reaming.

It will be understood that various changes may be made in the detail of construction without departing from the spirit or scope of the invention as defined by the appended 115 claims.

I claim:

1. An underreamer comprising a slotted body presenting an interior cylindrical surface, a conical wedge having a bore therethrough disposed in said body, blocks carrying cutters slideable in said slots having their inner sides engageable upon the wedge, said blocks having lateral wings extending laterally beyond the sides of the slots between the wedge and the body, a piston disposed 120

within the body below said blocks, and means for causing fluid discharged through said wedge to build up a pressure beneath said piston, causing it to lift said blocks into engagement with said wedge, so that they will be expanded thereby.

2. An underreamer comprising a slotted body presenting an interior cylindrical surface, a conical wedge having a bore therethrough disposed in said body, blocks carrying cutters slideable in said slots having their inner sides engageable upon the wedge, a piston disposed within the body and about the lower end of said wedge, said piston being arranged below said blocks, and means for causing fluid discharged through said wedge to build up a pressure beneath said piston, causing it to lift said blocks into engagement with said wedge, so that they will be expanded thereby.

3. An underreamer comprising a slotted body presenting an interior cylindrical surface, a conical wedge having a bore therethrough disposed in said body, blocks carrying cutters slideable in said slots having their inner sides engageable upon the wedge, a piston disposed within the body and about the lower end of said wedge, said piston being arranged below said blocks, and means for causing fluid discharged through said wedge to build up a pressure beneath said piston, causing it to lift said blocks into engagement with said wedge, so that they will be expanded thereby, said blocks having lateral wings extending laterally beyond the sides of the slots between the wedge and the body.

4. An underreamer comprising a slotted body presenting an interior cylindrical surface, a conical wedge having a bore therethrough disposed in said body, blocks carrying cutters slideable in said slots having their inner sides engageable upon the wedge, said blocks having lateral wings extending laterally beyond the sides of the slots between the wedge and the body, a piston disposed within the body below said blocks, and means for causing fluid discharged through said wedge to build up a pressure beneath said piston, causing it to lift said blocks into engagement with said wedge, so that

they will be expanded thereby, said piston having a conical bore therein complementary to the surface of the wedge.

5. An underreamer comprising a slotted, hollow body, a wedge disposed in said body, blocks carrying cutters slideable in the slots, said blocks being engageable upon said wedge so as to be expanded thereby and carrying lateral wings in sliding engagement with the inner circumference of the body to prevent the blocks from being withdrawn from the slots, a piston slideable in the body below the blocks, said wedge having a bore therethrough through which fluid may be discharged, and means for causing the fluid discharged through said wedge to build up a pressure below the piston to cause the piston to lift the blocks into engagement with the wedge so as to be expanded thereby.

6. In a hydraulically operated underreamer, means for preventing a fluid pressure from building up within the underreamer on lowering it into a well, comprising a valve seat mounted in the passage above the reamer through which fluid pressure is supplied to the reamer, and a valve adapted to seat thereon, there being passages communicating with the exterior of the tool and the interior of the valve seat below the valve and passages arranged through the valve seat for the purpose described.

7. In a hydraulically operated well drilling tool, a tubular body through which fluid is adapted to be forced, a valve seat mounted in said body, a valve adapted to seat thereon, means closing the bottom of the valve seat, there being passages formed in the tubular body and in the valve seat establishing communication between the exterior of the body and the interior of the valve seat above said closing means, there being passages formed in the valve seat forming by-passes about the valve permitting fluid to be forced through the valve seat within said tubular body.

In testimony whereof I have signed my name to this specification.

B. F. BLANCHARD.
